UNITED STATES PATENT OFFICE.

MARK P. BURKE, OF TULSA, OKLAHOMA.

DRIVING MECHANISM FOR OIL-WELL RIGS.

Application filed December 1, 1924. Serial No. 753,291.

To all whom it may concern:

Be it known that I, MARK P. BURKE, a citizen of the United States, and residing at Tulsa, county of Tulsa, Oklahoma, have invented the new and useful Improvement in Driving Mechanisms for Oil-Well Rigs, of which the following is a specification.

This invention pertains to driving mechanism for oil well rigs.

10 The driving mechanism of the standard oil well rig usually includes a band wheel suitably driven by an engine or other prime mover, a crank on the band wheel shaft suitably connected to a walking beam and a connection from the walking beam leading into the well. Such a connection may take the form of a pump rod which reciprocates in the well to drive the pump at the bottom thereof. In some cases, however, as for instance, in the drilling operation when the cable is given a jerking movement or in the operations of pulling tubes or rods from the well which are simple hoisting operations, the connection is not given the simple reciprocating movement. During the pumping operation the pump rods which may be two or three thousand feet in length and may weigh two or three thousand pounds are hung directly on one end of the walking beam. This weight must be stopped, started and accelerated for each stroke of a pump and it is desirable, therefore, to counter-balance the same so as to reduce the amount of power required to operate the pump. During the hoisting operations, such as pulling tubes or rods, there is no necessity for a counter-balance of any kind.

One of the objects of this invention, therefore, is to provide means for counter-balancing a standard oil well rig in such a way as to assist in pumping and similar operations without interfering with other operations.

Another object is to provide counter-balancing means which may be disconnected and moved out of the way when not required.

Another object is to provide a novel form of counter-weight adapted for interlocking engagement to retain the same in place.

Further objects will appear from the following description taken in connection with the accompanying drawing in which:

Figure 1 is a side view of a standard band wheel equipped with a counter-balance in accordance with this invention;

Figure 2 is a fragmentary sectional side view of Figure 1;

Figure 3 is a section on line 3—3 of Figure 1;

Figures 4 and 5 are plan views of counter-weight sections embodying this invention;

Figure 6 is a perspective sectional view of a set of interlocking counter-weights embodying this invention; and

Figure 7 is a side view on a reduced scale of an oil well rig embodying this invention.

Referring to the accompanying drawing 1 designates a band wheel such as may be found on the usual standard oil well rig. The band wheel is usually mounted on a band wheel shaft 2 to which is fixed a crank 3 adapted for connection by a pitman 4 to the walking beam 5 of the rig. The walking beam may be pivoted on a Samson post 6 and have suitable connected at its opposite end a connection 7 leading into the well.

In accordance with this invention a bearing 8 is provided which is constructed in two half parts adapted for assembly surrounding the shaft 2 as shown in Figure 1. The bearing is loose on the shaft so as to be able to turn thereon and a suitable grease or oil cup 9 provides for lubrication thereof.

Connected to the bearing 8 by means of a pair of rods or bolts 10 is a counter-balance comprising a head 11 through which the bolts 10 may pass, and a series of counter-weight sections 12 also mounted on the rods 10 and connected with a head 11 by means of bolts 13. The head 11 is provided with brackets 14 by means of which the counter-balance may be fixed to the band wheel 1 by bolts 15.

It is thus provided that the counter-balance may be detachably connected to the band wheel. The counter-balance is preferably attached to the band wheel in the position shown in Figures 1 and 7, that is, on the same side of the band wheel toward which the crank 3 extends. In this position the counter-balance will always be in the proper relation to balance the weight of the connection 7 leading into the well.

When connected in this way the counter-balance rotates with the band wheel during the pumping operation. On the up-stroke of the pump connection the counter-weight

will be moving down and its weight and momentum will assist in lifting the pump.

connections. On the down stroke of the pumping connection the counter-balance will be moving upwardly so that the weight and momentum of the pump connections 5 will also be effective in lifting the counter-balance. Conversely the counter-balance prevents a too rapid descent of the pump connections. This construction, therefore, provides for a more uniform movement with 10 a less expenditure of power for pumping and consequently a less severe service on the prime mover.

During drilling or hoisting operations or the like, it is undesirable to have a counter- 15 balance attached to the band wheel. During such operations, therefore, the bolts 15 may be removed and the counter-balance detached from the band wheel. The band wheel may now rotate freely without the 20 counter-balance which simply hangs in a vertical position with the shaft 2 turning in the bearing 8. The bolts 10 pass through flared holes 16 in the halves of the bearing 8 so as to permit the rods 10 to be swung 25 sidewise after loosening the nuts 17 which clamp the bearing 8 in assembled relation. This provides that when detached from the band wheel the counter-balance may be 30 swung clear of the wheel as indicated by the dotted positions shown in Figures 2 and 3. In this position the counter-balance may be tied to the jack-post 18 so as to keep it out of the way of the band wheel.

The counter-weight sections 12 may be 35 provided with side slots 19 adapted to be slipped over the rods 10 in assembling these sections to form the counter-balance. Bolt holes 20 are also provided to receive the 40 bolts 13. In accordance with this invention the counter-weight sections are formed to interlock with one another as shown in Figures 4, 5 and 6. In Figures 4 and 5 the ends of the sections are provided with interlocking tongues 21 adapted to maintain the 45 sections in proper alinement. In the embodiment illustrated in Figure 6, which shows a section taken through one of the slots 19, each section is provided with a projection 22 and a corresponding recess 50 23 is arranged so that when the sections are stacked one upon the other the projections 22 of one will engage the recesses 23 of another so as to maintain the stack in assembled relation and in alinement.

55 It will be seen, therefore, that in accordance with this invention a novel counter-balance is provided which may be mounted directly on the band wheel shaft and suitably adjusted so as to counter-balance the 60 weight of the connection leading into the well. When desired the counter-weight may be detached from the band wheel by a simple operation quickly made and may be 65 swung clear of the wheel so as not to interfere with its operation. The counter-bal-

ance may be adjusted to any desired weight by adding or subtracting sections 12. These sections when assembled interlock so as to maintain their alinement and avoid the possibility of their coming loose during opera- 70

It is obvious that various changes may be made in the details of construction without departing from the spirit of this invention; it is to be understood, therefore, that this 75 invention is not to be limited to the specific details shown and described.

Having thus described the invention what is claimed is:

1. Driving mechanism for oil well rigs, 80 comprising, a drive shaft, a crank thereon, a walking beam connected to be operated by said crank, connections from said walking beam and leading into the well, a counter-weight adapted to cooperate with said shaft, 85 and connections adapted to fix said counter-weight so as to move with said shaft, said connections being releasable so as to permit said shaft to move without said counter-weight.

2. Driving mechanism for oil well rigs, comprising, a drive shaft, a crank thereon, a walking beam connected to be operated by said crank, connections from said walking beam and leading into the well, a counter-weight adapted to cooperate with said shaft, 95 and connections adapted to fix said counter-weight so as to move with said shaft in a predetermined relation with respect to said crank, said connections being releasable so as to permit said shaft to move without said counter-weight.

3. Driving mechanism for oil well rigs, comprising, a band wheel, a crank, a walking beam driven thereby, connections from 105 said walking beam and leading into the well, a counter-weight permanently mounted on the band wheel shaft adapted to cooperate with said wheel, and means for connecting said counter-weight to move in fixed relation with the band wheel, said connections being releasable so as to permit said wheel to move without said counter-weight.

4. In a deep well having a string of tubing and a string of pumping rods operable therein, a power rig having driving mechanism comprising, a drive shaft, a crank thereon, a walking beam connected to be operated by said crank, connections from 110 said walking beam to the pump rod string, a counter-weight adapted to cooperate with said shaft in order to counter-balance the pump rod string, and connections adapted to fix said counter-weight so as to move with said shaft, said connections being releasable so as to permit said shaft to move without said counter-weight.

5. Driving mechanism for oil well rigs, comprising, a band wheel, a crank, a walking beam connected to be driven by said 120

- crank, a connection from said walking beam and leading into the well, a counter-balance, rotatable on the band wheel shaft, and means for attaching said counter-balance to the well, a bearing on said shaft, and a counter-balance flexibly mounted on said bearing and attachable to said band wheel. 25
- 5 move in fixed relation with said crank.
6. Driving mechanism for oil well rigs, comprising, a band wheel, driving connections including a shaft from said wheel and leading into the well, and a counter-balance 10 movable on said shaft and detachably connected to move in fixed relation to said band wheel.
7. Driving mechanism for oil well rigs, comprising, a band wheel, a shaft therefor, 15 a walking beam driven thereby, a connection from said walking beam and leading into the well, a bearing on said shaft, and a counter-balance mounted on said bearing and attachable to said band wheel.
- 10 8. Driving mechanism for oil well rigs, comprising, a band wheel, a shaft therefor, a walking beam driven thereby, a connection from said walking beam and leading into the well, a bearing on said shaft, and a counter-balance flexibly mounted on said bearing and attachable to said band wheel. 30
9. In a driving mechanism for oil well rigs, a drive shaft, connections from said shaft leading to the well, an arm on said shaft, and a counter-weight on said arm including a head and a series of sections detachably interlocked with said arm and secured to said head. 35
10. In a driving mechanism for oil well rigs, a drive shaft, connections from said shaft leading to the well, an arm on said shaft, and a counter-weight on said arm including a head and a series of mutually interlocking sections having recesses therein adapted to interlock with said arm, and 40 means for detachably securing said head and said sections together.

In testimony whereof I affix my signature this 25th day of November, 1924.

MARK P. BURKE.
